(57) **CLAIM**

The ornamental design for a vehicle roof top tent, as shown and described.

DESCRIPTION

FIG. 1 is a perspective view of a first embodiment of the vehicle roof top tent shown on a vehicle.

FIG. 2 is a perspective view of the vehicle roof top tent.

FIG. 3 is a front elevational view of the vehicle roof top tent.

FIG. 4 is a rear elevational view of the vehicle roof top tent.

FIG. 5 is a left side elevational view of the vehicle roof top tent.

FIG. 6 is a right side elevational view of the vehicle roof top tent.

FIG. 7 is a top plan view of the vehicle roof top tent.

FIG. 8 is a bottom plan view of the vehicle roof top tent.

FIG. 9 is a top plan view of a second embodiment of the vehicle roof top tent, the front elevational view, the rear elevational view, the left side elevational view, the right side elevational view and the bottom plan view being the same as shown in FIGS. 3-6 and 8.

FIG. 10 is a top plan view of a third embodiment of the vehicle roof top tent, the front elevational view, the rear elevational view, the left side elevational view, the right side elevational view and the bottom plan view being the same as shown in FIGS. 3-6 and 8; and,

FIG. 11 is a top plan view of a fourth embodiment of the vehicle roof top tent, the front elevational view, the rear elevational view, the left side elevational view, the right side elevational view and the bottom plan view being the same as shown in FIGS. 3-6 and 8.

The broken lines on the bottom surfaces illustrate portions of the vehicle roof top tent which form no part of the claimed design. The broken lines on the top, left, right, front and rear surfaces show stitching which is part of the claimed design. The broken lines showing a vehicle in FIG. 1 depicts environmental structure which forms no part of the claimed design.

1 Claim, 10 Drawing Sheets
